(57) CLAIM

The ornamental design for a seat cushion, as shown and described.

DESCRIPTION

FIG. 1 is a perspective view of the seat cushion embodying the design.

FIG. 2 is a front view of the seat cushion.

FIG. 3 is a top view of the seat cushion; and,

FIG. 4 is a right side view of the seat cushion.

The left side view is a mirror image of FIG. 4. The broken line showing of the environment is for illustrative purposes only and forms no part of the claimed design. The bottom and rear views are not part of the claimed design.

The broken line showing of the stitching on the seat cushion is for illustrative purposes only and forms no part of the claimed design.

1 Claim, 3 Drawing Sheets

Fig. 2.
